UNITED STATES PATENT OFFICE.

EDGAR B. NICHOLS, OF ROCHESTER, NEW YORK.

CHAIN-LINK CONSTRUCTION.

Application filed April 12, 1919. Serial No. 289,664.

To all whom it may concern:

Be it known that I, EDGAR B. NICHOLS, a citizen of the United States, and a resident of Rochester, county of Monroe, and State of New York, have invented a certain new and useful Chain-Link Construction; and I do hereby declare that the following is a full, clear, and exact description thereof, reference being had to the accompanying drawings, in which like numerals refer to like parts.

This invention relates to chain links of the block type and is an improvement over the form of link shown in my former application Serial No. 225,998 filed April 1, 1918.

The feature of the present invention is in forming the link from one piece of metal and bending the same so as to provide holes at the end thereof for the reception of pivoted pins such as are used in connecting the side plates of the ordinary construction to the block portion of the link.

A further feature of the invention is in so arranging the parts of the metal forming the block portion of the link as to give added strength thereto without materially adding to the weight of the block, and at the same time lessen the cost of production of all the parts of the link.

30 A further feature of the invention is in so constructing the material, which consists of a section of flat sheet metal, that the fibre of the metal will preferably run parallel with the stress in the link and will extend around the pins of the chain.

35 A further feature of the invention is in so forming the parts of the link structure that said parts, when completed, will interlock, such interlocking parts rendering it possible, 40 under certain conditions, to dispense with welding the parts of the link structure together at a point between the openings for the pivot pins.

In the accompanying drawings, which are 45 made a part of this application, Fig. 1 is a perspective view of the block portion of a link showing the meeting ends thereof interlocked together. Fig. 2 is a similar view showing the interlocking ends after the same 50 have been welded together. Fig. 3 is a perspective view of a different form of locking means. Fig. 4 is a perspective view of a further modified form of locking means for the ends of a link structure. Fig. 5 is a top 55 plan view thereof. Fig. 6 is a perspective view of a further modified form of inter-

locking means. Fig. 7 is a top plan view thereof.

In the form of structure shown the block portions of the link are formed from sheets 60 of metal, which sheets are of proper width to form parts of the chain structure, and these widths may be varied in accordance with the different widths of links desired, or increased to correspond with the size of the 65 sprocket with which the links cooperate. The block link 10 is formed by bending the ends 11 and 12 of the strip in loop formation until said ends are brought together over the middle portion of the metal strip, the 70 end 11 having an inwardly bent portion 13, while the end 12 is bent to form a channel 14 into which the end 13 seats, thereby interlocking said ends together, which completes the formation of a block link when the same 75 is to be used with a chain having a minimum amount of stress thereon. When the chain structure is to be subjected to heavier strain, the ends 11 and 12 are welded together and to the middle portion of the strip as best 80 shown at 15 in Fig. 2 of the drawings. The ends of the strip of metal, after being interlocked, are preferably forced inwardly until they rest against the middle portion of the strip so as to form pin openings 16 at each 85 end of the completed block link.

In Fig. 3 of the drawings the end 11^a of the metal strip 10^a is bent substantially L-shaped, as indicated at 17, while the end 12^a is provided with a substantially L-shaped 90 channel 18 for the reception of the end 17. In Fig. 4 of the drawings the metal strip 10^b is similar to the structure shown in Figs. 1 and 2, except that the ends 11^b and 12^b are slit longitudinally to form tongues 19, 20, 95 21 and 22 respectively, the tongue 19 having a depending end 23 which engages a channel 24 formed in the end of the tongue 21. The tongue 20 is bent to form a channel 25 for the reception of the projection 26 on the 100 tongue 22, the ends 11^b and 12^b having reversed and adjacent tongue and groove connections, (see Figs. 4 and 5).

Figs. 6 and 7 show a further modified interlocking structure, in that each of the ends 105 11^c and 12^c are prolonged, the width thereof reduced substantially one half to form tongues 27 and 28 respectively on the parts 11^c and 12^c, the inner edge of said tongues having lateral extensions 29 and 30 which 110 enter offsets 31 and 32 in the inner edges of the tongues 27 and 28 respectively, while the

ends of the tongues are provided with extensions 33 and 34 respectively which enter recesses 35 and 36 respectively, thus forming a lock against longitudinal as well as lateral strain in the parts of the link structure.

Under normal conditions the interlocking features of the various forms of link structure shown will be sufficient to produce a finished structure, but it will be understood 10 that in addition to providing these interlocking features the folds of the strip of metal may be welded together so as to form a solid structure, this being preferable where the block link of a chain is formed of the 15 sheet metal strip and subjected to very heavy strain.

In preparing the strips of metal they are cut from a sheet of metal, and longitudinally thereof so that the fibre of the metal will extend longitudinally of the strip, whereby 20 when the strips are bent into proper shape to form the block links, the fibre of the metal will run parallel with the strain and will extend around the pins employed for securing 25 the link blocks into chain formation. By constructing the link in this manner the cost of manufacture thereof is very greatly reduced as they can be manufactured with less effort and the strength thereof maintained 30 and multiplied without adding to the cost of production.

The invention claimed is:

1. The process of forming a link for sprocket chains consisting in bending the

ends of a flat strip of metal transversely 35 upon the middle portion thereof, and forming portions of the ends into a tongue and a groove respectively, and interlocking said ends in width-wise engagement, the edges of the strip being in alignment throughout. 40

2. The process of forming a link for sprocket chains consisting in bending the ends of a flat strip of metal toward each other to provide separated pin bearing loops; bending one half of each end toward and the 45 other half of each end away from the middle portion of the strip, and pressing the oppositely turned halves of one end into engagement with the corresponding portions of the other end of the strip.

3. The process of forming a link for sprocket chains consisting in bending a flat strip of metal upon itself so that the ends thereof are interlocked and are pressed upon the middle portion, leaving pin bearing 55 loops at the outermost bends, and securing said interlocked ends by welding.

4. The process of forming a link for sprocket chains consisting of bending width-wise a flat strip of metal and bringing the 60 ends thereof to the middle portion; interlocking the ends of the strip with each other, and pressing said interlocked ends upon the middle portion of the strip and securing them thereto by welding.

In witness whereof, I have hereunto affixed my signature.

EDGAR B. NICHOLS.
